UNITED STATES PATENT OFFICE.

HOWARD R. ROST, OF CHICAGO, ILLINOIS, ASSIGNOR TO CONTINENTAL DISTRIBUTORS,
INCORPORATED, OF CHICAGO, ILLINOIS, A CORPORATION OF ILLINOIS.

FIRE-EXTINGUISHER.

1,248,722.

Specification of Letters Patent.

Patented Dec. 4, 1917.

Application filed October 28, 1915. Serial No. 58,308.

To all whom it may concern:

Be it known that I, HOWARD R. ROST, a citizen of the United States, residing in Chicago, in the county of Cook and State of Illinois, have invented a new and useful Improvement in Fire-Extinguishers, of which the following is a specification.

This invention relates in general to fire extinguishers and has more particular reference to devices of this character provided for hand operation.

Prior to my invention hand fire extinguishers have been generally constructed of two kinds. In one kind the fire extinguishing material is expelled by pressure generated by a gaseous, semi-gaseous or liquid fluid. The use of this character of device has resulted in considerable loss by reason of the fact that in some instances the expelling fluid has been found to have been of relatively short effective life, and by reason also of the fact that in many instances the expelling fluid has been of highly destructive character and has frequently leaked out with great resulting damage to the person handling the extinguisher, and also to the burning object or building. The second class of devices of this kind have incorporated in their construction a hand pump or similar mechanism, which has, of course, required continued and forceful manipulation by the operator. The trouble with this sort of device is that its operation is of necessity slower and less efficient than a device wherein the power needed for its operation is stored in it ready for instant application.

The purpose of this invention is to provide a simple and effective hand fire extinguisher wherein a plunger for ejecting the fire extinguishing material will be held under high pressure without the utilization of any ejecting fluid which may escape and damage the user or surrounding property.

A further object of the invention is the provision of a fire extinguisher which when loaded will possess high ejecting powers readily releasable.

A still further object of the invention is the provision of such a device which may be re-filled without requiring the removal of any of the parts.

A still further object of the invention is the provision of such a device which will possess no valves or other delicate parts

likely to become disarranged or ineffective either from considerable use or through remaining inactive for a prolonged period.

A still further object of the invention is the provision of such a device that will require in its operation a single turning of a single member to bring it into full operation, parts being so constructed and arranged as to present little or no danger of inadvertent or premature operation of said device.

Other objects and advantages of the invention will be apparent as it is better understood from the following description when considered in connection with the accompanying drawing illustrating a preferred embodiment thereof.

Referring to the drawings:

Figure 1 is a longitudinal sectional view through a fire extinguisher embodying my present invention;

Fig. 2 is a front plan view of the hanger or bracket which is provided to support the same from a wall or the like;

Fig. 3 is an enlarged detail section showing a part of the locking device;

Fig. 4 is a section taken substantially on the line 5—5 of Fig. 1; and

Fig. 5 is a detail section showing a mechanism for charging the extinguisher.

In the embodiment of the invention illustrated on the drawing, A designates a casing in which is mounted a plunger B which divides the casing into two compartments, one, C, adapted for the containing of the fire extinguishing material and the other, D, in which is positioned means E for operating the plunger, said means being normally held against action by a locking device F.

The casing in the present instance comprises two cylindrical parts 11 and 12 connected together for communication by a threaded coupling 13. The part 11 is the larger and it is in this part that the plunger B moves. The outer end of the part 11 is threadedly engaged with an end piece 14 of conical form, in the apex of which is mounted a nozzle 15 having a restricted outlet 16. The plunger B in the embodiment of my invention shown on the drawing, serves both to eject fire extinguisher from the nozzle 15 and to charge the chamber C by drawing fire extinguishing material through the nozzle into the chamber. The plunger B is actuated by a pair of powerful

springs 17 and 18 which bear at one end upon the rear face or part 19 of the plunger and at the other on the inner face of an end closure 21 for the casing part 12, the 5 end closure 21 being in threaded engagement with the end of the cylindrical part 12. The springs 17 and 18 are arranged one within the other and are oppositely spiraled. A plunger rod 22 is engaged at 10 one end in the plunger and extends through the inner spring 18.

The plunger has a travel substantially equal to the length of the part 11 and it is normally held at the end of this part adjacent 15 to the part 12 by a locking device which will now be described. The plunger rod 22 is of length somewhat longer than the length of the part 12, so that when the plunger is in retracted position, shown in Fig. 1, the 20 plunger rod extends throughout the length of the part 12 and into an aperture 23 of a boss 24 formed on the end closure 21 for the part 12. A portion of the plunger rod thus extending into this aperture is cut 25 away on one side at 25 and in the recess thus formed extends a pivotally mounted locking member 26. This locking member is mounted in an aperture 27 extending at right angles to the aperture 23 and through 30 the boss 24. The locking element 26 is cut away at one side at 28 opposite the plunger rod 22 and the aperture 27 is arranged with respect to the aperture 23 so that the plunger rod and locking device interengage when 35 the locking device is moved to present a cylindrical part of its surface to the plunger rod. The recesses 25 and 27 in the plunger rod and locking member respectively, permit the plunger rod to be released when 40 these recesses are placed in adjacent relation. The end 29 of the locking member 26 is bent to provide a finger piece to facilitate movement of the locking device into and out of locking position. When in locked 45 position this finger piece is adapted to be embraced by a link 31 pivoted in a boss 32 on the side of the end closure 21. When the parts are arranged in normal position the link 31 extends about the finger piece 50 29 and prevents inadvertent release by the locking device.

The extinguisher may be charged after the parts have been assembled by dipping the nozzle 15 in a suitable material and 55 drawing the plunger up to retract the springs 17 and 18. This may be accomplished in a number of ways but I have shown on the drawing in Fig. 5 a simple mechanism for the purpose. This mechanism 60 consists in a staff 33 threaded throughout its length and adapted for threaded engagement at 34 in a threaded aperture 35 in the end of the plunger rod. A threaded hand nut or collar 36 may be turned down 65 on the rod 33 into engagement with the

outer end of the boss 24. Further turning of the hand nut will cause the staff 33 to pass out through the boss and draw with it the plunger rod, moving the plunger to retracted position. As the springs 17 and 18 70 are of considerable power, I find it desirable to provide one or more hand grips 37 extending out from the sides of the collar or nut 36. When the plunger rod has been pulled to the outmost limit of its movement, 75 the locking member may be turned to the position shown on the drawings and the link 31 engaged over the finger piece 29. The staff 33 and the collar may then be removed, leaving the parts in their operative 80 relations ready for instant use.

I preferably also provide a friction cap 38 to close the nozzle 15, and in order that this cap may not be lost I fasten it by a chain 39 to a washer 40 interposed between the end 85 of the end closure 14 and the nozzle 15. If desired this cap may be more tightly held in place by positioning it just before the plunger rod is drawn to the extreme limit of its charging movement. This creates a partial 90 vacuum within the extinguisher which aids in holding the cap in place. This cap need not of necessity be removed when it is desired to discharge the extinguisher, the pressure of the springs being ample to force 95 it from its seat.

While any form of plunger which will accomplish the desired results may be utilized, I have shown on the drawing a plunger composed of a forward metal member 100 41 and a rear metal member 42 embracing between them a washer 43 of leather or other suitable material, the edge 44 of this washer extending forward in contact with the inner face of the part 11.

On the drawing, G indicates a suitable support or hanger for this fire extinguisher and this hanger consists of a back plate 45 having at each end a ring 46 adapted to embrace the part 11, the internal diameters 110 of these rings being substantially that of the part 11 and the rings being spaced apart a distance which will bring them in contact with the inner end of the end closure 14 and the adjacent end of the coupling 13, both of 115 which parts are threaded onto the outside of the cylindrical part 11 of the extinguisher. The back plate 45 is provided with two inverted key-hole slots 47, the larger parts of which may pass over the heads 48 120 of suitably positioned screws and the narrower parts thereafter pass down around the stems 49 of said screws to hold the bracket in place. When it is desired to use the extinguisher, the extinguisher with its 125 bracket is removed and the finger piece released and turned to release the plunger rod to permit discharge of the fire extinguishing material.

It will be manifest that a large amount 13

of power for the operation of the extinguisher may be stored within it and this without requiring the provision of any gaseous liquids and also without requiring the provision of any valves or other parts requiring delicate adjustment.

The embodiment of my extinguisher just described may be made largely of sheet metal and can therefore be constructed of 10 relatively light weight.

The use of two springs is for the double purpose of providing sufficient power behind the plunger, *i. e.*, in practice in the neighborhood of 300 pounds pressure at the 15 beginning of discharge and about 200 pounds pressure at its end, and also providing for accurate guidance of the plunger rod during discharge and for the accurate guidance also of the rewind threaded rod 20 33. It will be understood that the inner spring has an internal chamber which when extended fits closely about the plunger rod.

A casing of the character described is of particular advantage in the use of the extinguisher as it adapts itself to ready and accurate aim. The large forward portion in which the material is contained can rest upon the palm of one hand of the user, and the rear portion be grasped in the manner 30 of a handle and moved from side to side and up and down to accurately direct the stream into the base of the fire.

It is thought that the invention and many of its attendant advantages will be understood from the foregoing description, and it will be apparent that various changes may be made in the form, construction and arrangement of the parts without departing from the spirit and scope of the invention 40 or sacrificing any of its material advantages, the form hereinbefore described being merely a preferred embodiment thereof.

I claim:

1. A fire extinguisher comprising in combination a casing, a plunger mounted to reciprocate in said casing and defining a chamber in front of it for fire extinguishing material, a spring behind said plunger for actuating said plunger, and means insertible 50 through the end of said casing behind said plunger for engaging said piston and operable with the end of said casing for returning said plunger to operative position after discharge.

2. A fire extinguisher comprising in combination a casing, a plunger mounted to reciprocate in said casing and defining a chamber in front of it for fire extinguishing material, a spring behind said plunger for actuating said plunger, and means insertible 60 through the end of said casing behind said plunger for engaging said piston and operable with the end of said casing for returning said plunger to operative position 65 after discharge, said means being guided

into engagement with said plunger by said spring.

3. In a fire extinguisher, the combination of a casing, a plunger mounted to reciprocate in said casing and defining a chamber 70 adapted to contain fire extinguishing material in front of it, a spring for operating said plunger and a staff insertible through the rear end of said casing and engageable with said plunger, an end of said staff being 75 disposed without the casing when the plunger is at the end of its discharge movement and adapted to be moved longitudinally of the casing to return said plunger to normal position. 80

4. A fire extinguisher comprising in combination a casing adapted to contain fire extinguishing material, a plunger for ejecting the same, and a pair of spiral springs bearing directly on the plunger and arranged one within the other for operating said plunger the casing having a central opening at its rear end. 85

5. A fire extinguisher comprising in combination a casing adapted to contain fire extinguishing material, a plunger for ejecting the same, and a pair of spiral springs oppositely coiled bearing directly on the plunger and arranged one within the other for operating said plunger the casing having a central opening at its rear end. 90

6. A fire extinguisher comprising in combination a casing adapted to contain fire extinguishing material, a plunger for ejecting the same, powerful pressure means acting 100 normally under stress upon said plunger, a locking device for holding said plunger against said pressure means, said locking device comprising a plunger rod movable with said plunger and having a recess in its side, 10 and a rotatable locking element presenting an irregular portion to said plunger rod, one position of said locking element causing said portion to engage in said recess to hold said plunger rod against movement and another position causing release of said rod. 110

7. A fire extinguisher comprising in combination a casing adapted to contain fire extinguishing material, a plunger for ejecting the same, powerful pressure means acting 115 normally under stress upon said plunger, a locking device for holding said plunger against said pressure means, said locking device comprising a plunger rod movable with said plunger and having a recess in its side, 120 and a rotatable locking element presenting an irregular portion to said plunger rod, one position of said locking element causing said portion to engage in said recess to hold said plunger rod against movement and another position causing release of said rod, and a member for embracing said locking member to hold it in locked position. 125

8. A fire extinguisher comprising a cas- 130

ing of large cylindrical diameter at its forward end and small cylindrical diameter at its rear end, a plunger mounted in the forward end of said casing and defining in 5 front of it a fire extinguishing chamber of large capacity and spring pressure means acting upon said plunger and positioned in the rear portion of smaller diameter of said casing, said rear portion being of proportioned diameter to be grasped by one hand 10

of a user and said forward portion being adapted to rest upon his other hand.

In testimony whereof, I have hereunto set my hand in the presence of two subscribing witnesses.

HOWARD R. ROST.
